METHOD OF AND APPARATUS FOR
HANDLING STRANDS

John W. Andrews, Westfield, N. J., assignor to
Western Electric Company, Incorporated, New
York, N. Y., a corporation of New York

Application January 13, 1931, Serial No. 508,470

8 Claims. (Cl. 242—42)

This invention relates to a method of and apparatus for handling strands and more particularly to a method of and apparatus for grouping electrical conductors in strand form.

In the manufacture of conductor quads, i. e., a group of four conductors intended as a component unit of a multi-conductor cable, it has been a practice, in some instances, to group two single conductors to form a pair and then group two such pairs to form a quad. Heretofore, in some cases, such individual pair has been permanently bound with cotton thread in order, among other reasons, to aid in making the two wires of the pair as nearly of the same length as possible.

An object of the present invention is to provide a method of handling strands which will be economical and facile and an apparatus for handling strands which will be simple and efficient.

The invention contemplates the positioning, side by side, of a pair of strands and the moving of the pair through an aligning zone wherein it is helically wrapped and unwrapped with a continuous travelling binding member.

Specifically, an individual strand is withdrawn from each of two adjacent supply spools by a continuously driven capstan and thence passed to a driven take-up reel. The two strands are passed through a tubular member which directs them in parallel relation through an aligning zone so that in passing to the capstan they advance in parallel, abutting throughout their longitudinal extents, while therein, as a single strand. A rotary carriage continuously tightly binds this pair helically with an endless travelling member for the purpose of locking the strands together and insuring that the same quantity of material of each strand shall be forwarded to the take-up irrespective of variations in their respective radii in passing over the capstan.

The invention will be more clearly understood from the following detailed description, read in connection with the accompanying drawings forming a part thereof, in which

Fig. 1 is a diagrammatic elevational view of an apparatus embodying the invention, and

Fig. 2 is a diagrammatic section taken on the line 2—2 of Fig. 1.

Referring to the drawings wherein similar parts are indicated in the two views by identical reference numerals, an apparatus, by means of which the method may be practiced, consists of a rigid framework generally designated by the numeral 10, comprising a base portion 11 surmounted by an upright supporting member 12. Spaced vertically aligned horizontal arms 13 and 14 pro-

ject from the base 11 and upright 12, respectively. A pair of strand supply reels 16 and 17 are rotatably mounted in stationary supports 18, 18 on parallel axes 19—19 and preferably so positioned respectively as to deliver strands drawn therefrom to a substantially common point. At the top of the apparatus a horizontal shaft 21, rotatably mounted at one end upon an inner gooseneck supporting bracket 22 and near the other end upon outer gooseneck supporting bracket 23, secured upon the horizontal arm 14, is provided at the outer end with a capstan 25 keyed thereto, and intermediately of its ends with a toothed wheel 26, suitably secured thereto as to be rotatable with the shaft 21. It will be understood that the brackets 22 and 23 are suitably apertured to receive the shaft 21 and constitute bearing members therefor. In order to prevent lateral movement of the shaft 21 with respect to the brackets, collars 27—27 are secured thereto upon either side of the bracket 22. A vertical shaft 28 suitably journalled in apertures 29—29 of the horizontal arms 13 and 14 extends downwardly from the top of the machine, and is provided at the upper end with a worm 30 secured thereto, and at the lower end with a bevel gear 31 suitably secured thereto.

A motor 32, suitably connected in any power supply line (not shown) is positioned in the base 11 and provided with a drive shaft 33 upon the end of which is fixed a bevel gear 34 which meshes with the bevel gear 31. From the foregoing it will be observed that when the motor 32 is in operation, the bevel gear 34 thereof meshing with the bevel gear 31 drives the vertical shaft 28. The worm 30 is positioned to mesh with the toothed wheel 26 to drive the capstan 25.

It has been found under normal conditions, that strands, upon movement from the supply spools around the capstan, will tend to lie either one upon the other during their contact with the surface of the capstan. Obviously, the superposed strand, having the larger radius, is thus advanced from its supply reel faster than the other strand, with the result that accidental twisting of one strand about the other, or curling or rumpling of one strand while the other remains straight, may become evident in the course of transfer from the supply reels. Not only may this unevenness result in a pair composed of component strands of unequal length, but may promise a pair of substandard or uncertain electrical characteristics when incorporated in a cable. In order, therefore, to insure that the strands drawn from the supplies as advanced to

the take-up by the capstan comprise a pair having component units of equal lengths for a certain length of the pair, the strands of the pair are secured together while advancing from the 5 supplies to the capstan to the end that different or changed radii in passing over rotating bodies such as the capstan 25 will be effectually prevented from causing one strand of a pair to be longer than the other. This is accomplished by 10 means of a carrier assembly which includes a tubular sleeve 35 perpendicularly disposed in an aperture 36 at the outer end of the arm 14. A gear 37 is secured to the exterior of the sleeve 35 above the arm 14 and provided with a locking collar 39 for affixing it to the sleeve 35 and maintaining the assembly in the aperture 36. Below the arm 14 a hollow spacer 40 surrounds the sleeve 35.

Bolted or otherwise suitably secured to the underside of the horizontal arm 13 is a U-shaped frame member 41. A tubular sleeve 42, similar to the sleeve 35, is secured in an aperture 43 of the frame 41. A hollow bushing 38 is rotatably suspended in the aperture 44 and surrounding the sleeve 21, and is provided below the arm 13 with a gear 46 affixed thereto by means of a collar 47.

A horizontal supporting arm 48 is secured to the bottom of the sleeve 35. This arm is apertured at 50 at one end to receive the sleeve 35 and at 51 in the opposite end to receive a pivotally mounted shank member 52, from which is suspended a guard 53 in which is rotatably mounted an idler pulley 54. The shank projects upwardly through the aperture 51, its upper end being provided with a nut 56 which is adjustable on the shank to control the tension in a compression spring 57 surrounding the shank 52. A supporting arm 58 is secured at one end on the bushing 38 and is provided at the other end with a pulley 59 rotatably mounted in a guard 60.

A gear 85 is secured to the shaft 28 between the worm 30 and the horizontal arm 14 to mesh with the gear 37 of the upper sleeve 35 and a gear 86 is secured to the vertical shaft 28 between the horizontal arm 13 and the bevel gear 31 to mesh with the gear 46 on the lower sleeve 42.

From the foregoing it will be observed that a strand 62 from the supply reel 16 and a strand 63 from the supply reel 17 may be moved into parallel and longitudinal abutment and held in such alignment to comprise a pair 64, which moves upwardly through the sleeve 42 to the lower end of the sleeve 35 whence it is passed around the capstan and under a tension pulley 65. The tension pulley is suspended from the U-shaped frame member 41 by means of any suitable spring 66 which acts to maintain the pair in tractive engagement with the capstan. A continuous travelling member 67 which may be of wire, textile, leather thong or other durable flexible material is passed within the guards 53 and 60 so as to rest upon the peripheries of the pulleys 54 and 59. The travelling member is wrapped helically about the pair as an axis a sufficient number of times to lock the strands thereof together, the member being sufficiently long to helically engage the pair over a substantial distance between the sleeve 35 and sleeve 42, and is always held tightly therearound by the tension of the spring 57.

A take-up reel 68, rotatable with an axis 70, is positioned in tandem relation with the supply reels 16 and 17, and is provided axially with a bevel gear 72. Suitable aligned auxiliary shafting

73—73 rotatably mounted in a three point bearing frame 74 is provided with a slip clutch 76 of any suitable type, that in the particular instance being shown having a compression spring 77, the force of which is sufficient to cause the take-up 80 to be driven from the motor 32 in conjunction with the carrier driving apparatus and yet decrease its rotation as the quantity of pair material on the take-up reel increases, thus permitting the speed of the strands moving through the apparatus to be maintained constant irrespective of the increasing circumference of the strand receiving surface of the take-up. The auxiliary shafting 73 is provided at one end with a bevel gear 78 which meshes with the bevel gear 72 and another bevel gear 79 is provided on the other end of the auxiliary shafting for engagement with the bevel gear 34 of the motor. Brake shoes 81—81 are provided on a stationary support 82 for preventing the supply reels from overrunning when the take-up is stopped and for always maintaining a modicum of tension in the strands 62 and 63.

In setting up the mechanism for operation the strands 62 and 63 from the supply reels 16 and 17, respectively, are drawn upwardly through the 100 sleeve 42 as pair 64, and the endless traveling member 65 is helically wrapped therearound, as by winding the pair preliminarily around the traveling member 65. The pair is then passed upwardly through the sleeve 35 and bushing 40 105 and passed around the periphery of capstan 25 any desired number of times, in the present instance being wrapped twice therearound. The pair is then carried downwardly, passed under the tension pulley 65, and secured to the take-up reel 110 68.

When the machine is in operation, sufficient tension is exerted in the strands by reason of the spring 66 to cause the pair to exert a moderate snubbing action on the periphery of the capstan in order that the latter may steadily draw the strands upwardly through the space between the sleeves 35 and 42, said space combining an aligning zone. The motor 32 drives the shaft 28 through the gears 34 and 31. Shaft 28 rotates 120 to drive the toothed wheel 26 through worm 30 and the gears 37 and 46 of the carrier mechanism through gears 85 and 86. The strands in passing through sleeve 42 are under sufficient tension by reason of the effect of the brakes 125 81—81 on the supply reels in order to cause them to be maintained taut. Immediately upon passing from the sleeve 42 the pair is concurrently engaged by the continuously traveling member 67 which is carried around the pair as an axis by the 130 rotating carrier arms 48 and 58, the bushing 40 and the collar 47 attached to the arms being driven by the gears 37 and 46, respectively. As the pair moves upwardly through the aligning zone the component strands thereof are continuously 135 tightly bound by the tensioned helically applied traveling member 67 so as to be tightly locked in longitudinal abutment. The upward movement of the pair tends to cause the member 67 to travel over pulleys 54 and 59 in the direction indicated 140 by the arrows (Fig. 2) so that the traveling member is concurrently unwound from any point in the strands and the strands freed at that point shortly prior to its passing through the sleeve 35 and simultaneously with the binding of a subsequent portion of the strand just emerging from the sleeve 42. Although in the embodiment illustrated the traveling member is wrapped around the advancing pair six times before the 145 strands are freed, it will be understood that the 150

- number of turns therearound may be varied as conditions warrant, it being only essential that the helical binding be sufficient to continually lock the strands in longitudinal abutment as they pass 5 through the aligning zone.
- From the sleeve 35 the strands pass over the capstan 25. Any tendency of the consequent change in their respective radii to cause one strand to be advanced faster than the other is 10 eliminated, due to the fact that the helical binding insures that the strands advance together and that as stored upon the take-up reels the pair shall be composed of component strands of equal lengths irrespective of the curvature of 15 the capstan surface.
- By practicing the above outlined method and by employing the above described apparatus in practicing the method, strands may be so handled as to form composite conductor strands composed of two or more components which will have 20 improved and uniform characteristics in an economical and facile manner. It will of course be understood however, that the specific apparatus described hereinbefore is only one of a number 25 of embodiments of the invention, and that various changes in the dimensions and arrangements may be made without departing from the scope of the invention as defined in the annexed claims.
- 30 What is claimed is:
1. In an apparatus for handling strands, means for supplying a plurality of strands, means for aligning the strands, means for advancing the strands through the aligning means, and endless means applied simultaneously for locking the strands in alignment and unlocking them.
  2. In an apparatus for handling strands, means for supplying a plurality of strands, a die for aligning the strands, means for continuously advancing the strands through the die, and means applied simultaneously for continuously locking the strands in alignment after exit from the aligning die and unlocking them upon their being advanced beyond the die.
  3. In an apparatus for handling strands, means for supplying a plurality of strands, means for continuously advancing the strands, means for aligning the strands in parallel and longitudinally abutting relationship, and means applied simultaneously engaging the strands after exit from the aligning means during their movement between the advancing means and the aligning means for locking the strands in alignment and unlocking them.
4. In an apparatus for handling strands, means for supplying a plurality of strands, means for continuously advancing the strands, means for aligning the strands in parallel and longitudinally abutting relationship, and means axially rotatable with respect to the strands applied simultaneously for locking the strands after exit from aligning means in alignment and unlocking them.
5. In an apparatus for handling strands, means for supplying a plurality of strands, means for continuously advancing the strands, means for aligning the strands in parallel and longitudinally abutting relationship, and means axially rotatable with respect to the strands for continuously applying an endless helical binding member to lock the strands in alignment.
6. An apparatus for forming composite strands, which includes a pair of rotatable supply reels, a take-up reel, a motor in operative engagement with the take-up reel, a capstan disposed above the supply and take-up reels, a horizontal shaft for the capstan, a toothed wheel thereon, a vertical shaft in operative engagement with the motor, a worm on the vertical shaft for engaging the toothed wheel to drive the capstan, a die for aligning a strand from each of the supply reels in parallel and longitudinally abutting relationship, a carriage rotatable axially with respect to a die, spaced idler pulleys on the carriage, spring retracting means for one of the idler pulleys, and an endless member on the pulleys for continuously helically binding the strands, locking them in parallel longitudinal abutment and adapted to be continuously removed from the strands when the locking engagement has been effected.
7. The method of forming composite strands which consists in continuously grouping and advancing a plurality of strands, and applying a separate member to the group to cause the strands thereof to abut along their longitudinal extent and to concurrently bind and unbind the group without changing the advancing direction of any strand of the group.
8. The method of handling strands which consists in continuously advancing a plurality of strands through an aligning zone wherein they are caused to be parallel and longitudinally abutting, continuously locking the strands in such relationship while in the zone, and unlocking the strands, the locking and unlocking of the strands being simultaneous operations accomplished by the application of an endless means.
